UNITED STATES PATENT OFFICE.

WILLIAM D. ARNOT, OF BELLEVUE, WASHINGTON.

COMBINED WRENCH AND PLIERS.

1,309,874.

Specification of Letters Patent. Patented July 15, 1919.

Application filed November 27, 1918. Serial No. 264,341.

To all whom it may concern:

Be it known that I, WILLIAM D. ARNOT, a citizen of the United States, residing at Bellevue, in the county of King and State 5 of Washington, have invented certain new and useful Improvements in Combined Wrenches and Pliers, of which the following is a specification.

This invention relates to tools, and more 10 particularly to combined wrenches and pliers.

The object of the invention is to provide a tool of this character constructed with parallel jaws capable of use either as a 15 wrench or as a pair of pliers.

Another object is to so construct such a tool that the element carrying the movable jaw will be always housed and in which the pressure exerted in closing the jaws is 20 directly below said element.

With the foregoing and other objects in view, which will appear as the description proceeds, the invention resides in the combination and arrangement of parts and in 25 the details of construction hereinafter described and claimed, it being understood that changes in the precise embodiment of the invention herein disclosed may be made within the scope of what is claimed without 30 departing from the spirit of the invention.

In the accompanying drawings:—

Figure 1 represents a side elevation showing one embodiment of this invention;

Fig. 2 is a similar view with parts broken 35 out and in section showing a slightly different form;

Fig. 3 is a detail bottom plan view of one of the jaws;

Fig. 4 is a similar view of the other jaw, 40 and

Fig. 5 is a detail side elevation with parts broken out and in section of a tool head embodying this invention in a slightly different form.

45 In the form shown in Fig. 1, an outwardly bowed handle 1 is shown carrying at its front end a fixed jaw 2 between which and said handle is a hollow head 3. Mounted to move in said head 3 is a movable jaw 4 which is arranged parallel with jaw 2 and is carried by a threaded bolt or shaft 5, said bolt in this form of the invention being shown made integral with the jaw 4, but which need not necessarily be so made as 55 will be hereinafter more fully explained.

This bolt 5 is movable through an opening 6 in the head 3 at the base of jaw 2 as is shown clearly in Fig. 2, the structure of Fig. 2 being identical with that of Fig. 1 in this particular, the only difference in these two 60 figures being that the handles are differently formed.

A knurled nut 7 is carried by the bolt 5 and is rotatable to move jaw 4 toward and away from jaw 2 when it is desired to adjust these jaws for different-sized work to be grasped when the tool is used as a wrench. The handle 8 of the structure shown in Fig. 1 is bowed oppositely to the handle 1 and carries at its inner end a head 9 which is 70 positioned within the head 3 and is fulcrumed at 10 carrying at its front end a pair of vertically spaced jaws 11 and 12 between which the nut 7 is designed to pass, as is shown in dotted lines in Fig. 1 and in full 75 lines in Fig. 2, so that when the handles are compressed toward each other, the jaws 2 and 4 will be closed in the same manner as a pair of pliers, the jaws moving in parallel relation to each other. A spring 80 11^a is arranged between the handles 1 and 8 being secured at one end to one handle and bearing at its other end against the other handle on its inner face and exerting its tension to normally hold said handles in 85 spaced relation and the jaws 2 and 4 open.

The structure shown in Fig. 2 as above stated is exactly the same as that shown in Fig. 1, except that the handles 1^a and 8^a are differently curved, being bowed in the same 90 direction so that handle 8^a with the head 9 carried thereby is substantially S-shaped and the spring 11^b which is arranged between them is differently curved to conform to the shape of the handles; otherwise the 95 structure is the same and operates in the same manner as that shown in Fig. 1.

In the form shown in Fig. 5, the handles are shown broken off and may be constructed like those in either of the above described 100 figures. The head 3^a of this tool is the same as that of the figures above described carrying at its lower front end a fixed jaw 2, and a movable jaw 4^a is mounted therein to move toward and away from jaw 2. This jaw 4^a 105 has threaded connection with the shaft 5^a instead of being made integral therewith as in the forms above described. The bolt 5^a has a knurled annular projection or flange 7^a made integral with its lower end, and 110

projecting from the lower end of said bolt below said flange is a stem 13 having a head 14. This knurled flange 7^a is movable in a chamber 15 in head 3^a so that on the turning 5 of said flange the bolt will be carried therewith and not be projected beyond the jaw 2 as is the case in the structure shown in the other figures, it being understood that the turning of this flange will operate to move 10 jaw 4^a to adjust it toward or away from jaw 2.

The handle 8^b of the tool shown in Fig. 5 carries at its front end a head 9^a which is curved outwardly and provided at its terminal with an aperture 16 through which passes the stem 13 carried by bolt 5^a, this aperture being flared toward its inner end and having a seat 17 in its outer end to receive the head 14 of the stem 13. The 20 spring 11^b shown in this figure is the same as that shown in Fig. 2 and operates in the same manner.

In the use of this tool it will thus be seen that by compressing the handles carrying 25 jaws 2 and 4^a said jaws will move toward each other in parallel relation and operate as a pair of pliers to grip the article and if desired they may be positioned toward or away from each other for use as a wrench 30 by adjusting the bolt 5^a by means of the flange 7^a.

From the foregoing description, taken in connection with the accompanying drawings, the advantages of the construction and 35 of the method of operation will be readily apparent to those skilled in the art to which the invention appertains; and while I have described the principle of operation of the invention together with the device which I 40 now consider to be the best embodiment thereof, I desire to have it understood that the device shown is merely illustrative and that such changes may be made as are within the scope of the claimed invention.

45 Having thus fully described my invention, what I claim as new and desire to secure by Letters Patent, is:—

1. In a tool of the class described, a handle having a head at one end provided 50 with a fixed jaw, a jaw movable in said head toward and away from said fixed jaw, a threaded shaft carrying said movable jaw, rotary means carried by said shaft operable to adjust said movable jaw, and 55 another handle pivoted to said head and

having a connection with said shaft to operate the tool as a plier.

2. In a tool of the class described, a handle having a head at one end with a fixed jaw extending longitudinally therefrom, a 60 jaw movable in said head toward and away from said fixed jaw, a threaded shaft carrying said movable jaw, and another handle pivoted to said head and having a swiveled connection with said shaft. 65

3. In a tool of the class described, a handle having a head at one end with a fixed jaw extending longitudinally therefrom, a jaw movable in said head toward and away from said fixed jaw, a threaded shaft, a 70 flange fixed to said shaft for turning it, said movable jaw having threaded connection with said shaft, another handle pivoted to said head and having a swiveled connection with said shaft. 75

4. In a tool of the class described, a handle having a head at one end with a fixed jaw extending longitudinally therefrom, a jaw movable in said head toward and away from said fixed jaw, a threaded shaft, a 80 flange fixed to said shaft, said movable jaw having threaded connection with said shaft, a stem depending from said shaft, a head on the lower end of said stem, another handle pivoted to said head with its front 85 end curved outwardly and provided at its terminal with an aperture through which said stem passes, said aperture being flared toward its inner end to permit swivel connection between said stem and handle. 90

5. In a tool of the class described, a handle having a head at one end provided with a fixed jaw and a recess, a jaw movable in said recess toward and away from said fixed jaw, said head having another recess 95 communicating with the recess in which said movable jaw is mounted and larger than said first-mentioned recess, an element carried by said movable jaw and located in said larger recess whereby the free movement of said jaw is limited, and a handle pivoted to said head and having a connection with said movable jaw to operate the tool as a plier. 100

In testimony whereof I affix my signature 105 in presence of two witnesses.

WILLIAM D. ARNOT.
